UNITED STATES PATENT OFFICE.

MICHAEL DILLORENZO, OF IRONDALE, WASHINGTON.

FARM-GATE.

1,101,167.

Specification of Letters Patent. Patented June 23, 1914.

Application filed May 26, 1913. Serial No. 769,846.

To all whom it may concern:

Be it known that I, MICHAEL DILLORENZO, a citizen of the United States, residing at Irondale, in the county of Jefferson and 5 State of Washington, have invented certain new and useful Improvements in Farm-Gates, of which the following is a specification.

This invention relates to farm gates, and 10 particularly to improvements in devices for actuating gates to open or close the same at a distance therefrom.

The object of the present invention is the provision of simple and effective mechanism 15 of the class described that will be positive and reliable in its action and strong and durable in the use for which intended.

A still further object of the invention is the provision of improved devices for unlatching the gate at either of said positions 20 in advance of the actuating movements of the gate.

With the above objects in view, the invention consists in the novel construction, combination and adaptation of gate-actuating, 25 latching and unlatching devices and other apparatus, as will be fully described in the following specification, illustrated in the accompanying drawings, and finally set forth 30 in the appended claims.

In said drawings, Figure 1 is a view in side elevation of a gate and actuating devices therefor embodying my invention. Fig. 2 is a fragmentary like view on a larger 35 scale. Fig. 3 is a rear elevational view of said actuating devices. Fig. 4 is a cross sectional view on line 4-4 of Fig. 2. Fig. 5 is a detail view of an element of the invention on line 5-5 of Fig. 2. Fig. 6 is a view 40 in side elevation and partly in vertical section of the latching devices; and Fig. 7 is a detached side elevation of the latch-lever.

Referring to said views, the reference numerals 1 and 2 indicate the main gate-posts 45 of a gateway and 3 a swinging gate of suitable construction swingingly connected to the latter post by means of pivotal connections at the upper and lower ends of its vertical end-bar 4 to brackets 5 and 6 rigidly 50 connected to said post, respectively. Said bar is provided at its upper end with a pin 7 pivotally mounted in bracket 5 and having a segmental bevel gear 8 keyed thereon above said bracket.

55 A horizontal shaft 9 is mounted to oscillate in upright angular portions 10 and 11

of said bracket 5. A segmental bevel pinion 12 is loosely mounted on said shaft in mesh with gear 8. The gate describes a course of approximately ninety degrees in opening to 60 its fullest extent, hence gear 8 may advantageously have, and is shown with, about ninety degrees of its circumference provided with teeth. The pinion 12 is in continuous mesh with the gear and is desirably of 65 larger radius. It is similarly unprovided with teeth for the larger portion of its circumference and is adapted to oscillate the gear by movements communicated by said shaft as follows:

13 indicate a pair of integral lugs projecting from the face of the pinion upon opposite sides of its axis and arranged symmetrically with respect to its teeth. A pin 14 projects from said shaft adapted to engage in turn upon the upper surfaces of said lugs and thereby to oscillate the pinion in the rotary direction of travel of the shaft. The rotary distance between said upper surfaces of the lugs upon the side opposite the 80 teeth of the pinion constitutes a period of travel of the shaft and its actuating pin 14 in each oscillation when said pinion is idle, the pinion being engaged and actuated by the pin in each oscillation during the latter 85 portion of the travel of the shaft.

Rigidly connected to the opposite end of the shaft 9 is a lever 15 having a weight 16 connected at its outermost end. Said lever is arranged at right angles to the axis of said 90 shaft and to be swung with said shaft on its pivot through a course of slightly more than one hundred and eighty degrees. Devices are arranged to raise the weighted end of said lever in its circular path over its center 95 of gravity, such upward travel of the lever corresponding to said idle movement of the pin 14 with relation to the lugs 13 of said pinion, while the actuation of pinion 12 occurs during the latter portion of each oscillatory movement of the lever through power derived from the fall of the descending weight 16 after it has passed over its center. Said lever 15 is actuated, as described, by the passengers through cable pulls 17 and 100 17¹ extending a distance from the gate in opposite directions and respectively running over pulleys 18 upon posts or supports (not shown) upon opposite sides of the gate. The other ends of said cables are respectively connected to the upper legs of opposite 110 directed bell-crank levers 19, 19¹ piv-

totally mounted on cross-beam 20 of post 2. The lower legs of said bell-cranks are respectively connected to an end of links 21, 21¹ whose opposite ends connect to pivotal pin 22 of an arm 23. Said arm is pivotally connected at 24 to said lever 15 and is formed at its inner end with forked branches 25, 25¹ extending upon opposite sides of shaft 9. Loosely mounted on said shaft in the same vertical plane as said branches is a vibratile cam 26 having its cam-face uppermost and formed with two protuberances 27 and 27¹ adapted to engage alternately the uppermost of branches 25 or 25¹, respectively, thereby locking the arm rigidly with the lever during the upward travel of the latter and adapted to tilt the arm 23 downwardly in advance of the lever 15 in the latter portion of each of their oscillating movements. A protruding pin 28 extends from one face of said cam toward the post 2 and engages alternately stops 29, 29¹ secured to the post limiting the vibratile movement of the cam, as indicated in full and dotted lines in Fig. 5. The chief function of said cam devices is to rock the connecting arm 23 through which the lever is actuated by said cables and intermediate connections independently of the general oscillatory motion of the lever and connected parts for the purpose of advancing the lever beyond the dead-center at each of its oscillations and in advance of the arm 23 so that when the latter is upon its dead-center the lever is inclined toward the direction it is traveling and its weighted end 16 then gravitates downwardly and furnishes the motive power for opening or closing the gate.

Assuming that the lever and connected parts are in the positions indicated in full lines in Fig. 5 with the gate closed, a pull upon either of cables 17 or 17¹ will influence the respective bell-crank 19 or 19¹ and its connected link 21 or 21¹ to exert a pull upon the arm 23. The cam 26 is in engagement with the uppermost of said branches, in this case indicated by 25¹, and secures the arm in temporary rigid relation to the lever. Thus the lever is raised with the arm which movement is likewise communicated to the cam as the pressure of the branch 25¹ upon its uppermost protuberance 27¹ is sufficiently direct toward the shaft to secure it in place while such lifting pressure is being exerted.

As the travel of the lever brings it to nearly a vertical position, the pin 28 of the cam engages the stop 29¹ and causes the cam to stop and remain at rest in the position indicated in dotted lines in Fig. 5. The arm 23 has progressed to dead center while the lever is descending on the downward operative portion of its travel wherein the weight 16 asserts itself. When the progress of the cam is checked the branch 25¹ slides thereover and beyond, while the branch 25 follows and

engages the cam at its uppermost protuberance 27, as the lever-parts approach their lowermost position. Said branch is thus deflected upwardly while the oppositely disposed arm 23 is rocked downwardly, as indicated in dotted lines in Fig. 5. The arm 23 is thus rocked upon the lower side of the lever and when the movements just described are reversed in closing the gate, the arm will be upon the rearward side of the lever and serve to advance the latter beyond the center where its gravity will be effective in actuating the gate.

By the described operation the gate is opened by a pull upon either cable 17 or 17¹ and may be closed by the same means.

Referring to Fig. 2, the numeral 30 indicates a cam-element keyed to shaft 9 and engaging an arm of a bell-crank lever 31. A cable 32 is secured to the opposite arm of the lever which runs over sheave 33 in the end-bar 4 of the gate, whence it extends and is connected at its opposite end to a lug 34 of a latch-lever 35 pivotally mounted in bracket 36 and adapted to engage a stop, hereinafter described, in the gate-post 1 and likewise with a similar stop in a post (not shown) spaced from the gateway and adapted to secure the gate in its open position.

Prior to the actuating portion of the travel of shaft 9 the cam-element 30 engages the shorter arm of said lever 31 and thereby pulls the cable 32 and raises the latch 35. As the shaft progresses, the cam releases the lever 31 and the weight of the longer arm of said lever and the weight of said latch return the lever and cable to their normal positions wherein the latch is free to be raised by engagement with a stop. In this connection it may be stated that a rearward projection 37 is formed upon said latch-lever to make it convenient for passengers to unlatch the gate without manipulating the gate-actuating devices. A stop for said latch, see Fig. 6, comprises a rod 38 slidably mounted in a chambered casing 38¹ mortised in gate-post 1 of the aforesaid retaining post at one side of the gateway. A nut 39 is fixedly secured to said rod within the casing chamber and coil springs 40 and 40¹ are interposed upon the opposite sides of said nut and the respective adjacent ends of the casing. At the forward end of said rod is a head 41 affording an abutment for the gate in closing having a forwardly directed integral extension 42 to whose extremity a tiltable wing 43 is pivotally mounted. The forward end of said wing is heavier and normally impinges upon a rest 44 maintaining the straight upper edge 45 at a suitable angle and the inner vertical edge 46 elevated above said extension to retain the latch in locked condition and which is spaced from the head 41 sufficiently to accommodate the latch-bar 35. When the gate is being closed,

the latch-bar 35 engages the wing 43 whose inclination raises the bar while at the same time the wing is tilted downwardly at its inner end as the bar progresses past its pivotal connection. The bar then impinges upon the head 41 and the wing is released and rocks upwardly at its inner end due to the gravity of its opposite end. At times the gate is closed with some force causing a sudden rebound that would sometimes result in the wing not holding the bar; to remedy the same and also to effect a cushioned stop for the gate the springs 40, 40¹ are provided, whose use will be readily understood.

As fully explained, the gate is actuated by the gravity of a weighted lever falling through a limited space. Such power is practically uniform being apportioned to supply just sufficient force to close or open a gate under usual conditions. At times it is found that the wind when blowing strongly, adversely affects the gate-actuating functions of the mechanism through accelerating the speed of the gate unduly or, more seriously, preventing its opening or closing entirely through the leverage upon the long sweep of a farm gate. To obviate this difficulty, an equalizing vane 47 is rigidly secured to the rear-bar 4 extending for a distance upon the opposite side of said pivots 5 and 6 as the gate proper 3 and in the same plane. Said vane is imperforate and presents a surface to the wind in a measure counterbalancing the wind-pressure upon the gate proper and offsetting any variation in speed due to the wind.

What I claim as my invention, is —

1. Gate-actuating mechanism comprising, in combination, a bracket-support, a swinging gate pivotally mounted on said bracket, a gear secured to the pivot of the gate, a shaft journaled for oscillation in said bracket, a pinion loosely connected to said shaft and meshing with said gear, devices on said shaft engageable with said pinion for actuating the pinion during the latter portion of its travel, a weighted lever rigidly connected to said shaft, and means for manually raising said lever over the center of the shaft.

2. Gate-actuating mechanism comprising, in combination, a bracket-support, a swinging gate pivotally mounted on said bracket, a gear secured to the pivot of the gate, a shaft journaled for oscillation in said bracket, a pinion loosely connected to said shaft and meshing with said gear, said pinion provided with a pair of spaced abutments, devices on said shaft engaging for a portion of its travel with one or the other of said abutments, a weighted lever rigidly connected to said shaft, and means for manually raising said lever over the center of the shaft.

3. Gate-actuating mechanism comprising, in combination, a gate-post, a gate swingingly mounted on said gate-post, a bevel gear operatively connected to said gate, a shaft journaled on said post, a bevel-pinion loosely mounted on said shaft and in mesh with said gear, protruding devices on said shaft engageable with said pinion and actuating same during a portion of its travel, a lever rigidly connected with said shaft and provided with a weight at its outer extremity, link devices connected to said lever, and cables connected to said link devices and respectively extending to a distance upon opposite sides of the gate.

4. Gate-actuating mechanism comprising, in combination, a gate-post, a gate swingingly mounted on said gate-post, a bevel gear operatively connected to said gate, a shaft journaled on said post, a bevel-pinion loosely mounted on said shaft and in mesh with said gear, protruding devices on said shaft engageable with said pinion and actuating same during a portion of its travel, a lever rigidly connected with said shaft and provided with a weight at its outer extremity, an arm pivotally connected to said lever, means for securing said arm in inclined relation to the lever and shifting said arm at each oscillation of the lever, link devices connected to said arm, and cables connected to said link devices and respectively extending to a distance upon opposite sides of the gate.

5. Gate-actuating mechanism comprising, in combination, a gate-post provided with a bracket-support, a swinging gate pivotally mounted in said bracket, a gear operatively connected to said gate, a shaft journaled for oscillation in said bracket, a pinion loosely mounted on said shaft in mesh with said gear, devices on said shaft engageable with the pinion for actuating the pinion during the latter portion of its travel, a weighted lever rigidly connected at right angles to said shaft, an arm pivotally connected to said lever, link devices pivotally mounted on said post and having one end connected to said arm, cables attached to said link devices extending to a distance upon opposite sides of said gate, respectively, and means whereby said arm is locked rigid with the lever at the earlier portion of each oscillation and is deflected into angular relation with the lever during the latter portion of each oscillation.

6. Gate-actuating mechanism comprising, in combination, a gate-post provided with a bracket-support, a swinging gate pivotally mounted in said bracket, a gear operatively connected to said gate, a shaft journaled for oscillation in said bracket, a pinion loosely mounted on said shaft in mesh with said gear, devices on said shaft engageable with the pinion for actuating the pinion during the latter portion of its travel, a weighted

lever rigidly connected at right angles to said shaft, an arm pivotally connected to said lever, link devices pivotally mounted on said post and having one end connected to said arm, cables attached to said link devices extending to a distance upon opposite sides of said gate, respectively, said arm having forked branches upon its end opposite to said link connections, a cam mounted on 5 said shaft interposed between the latter and one of said branches to lock the arm in rigid relation to the lever and whereby the engaged branch is deflected to rock said arm in angular relation to said lever at each oscillation.

7. In a swinging-gate, latching apparatus comprising, in combination, a gate, an oscillating shaft, power mechanism actuating said shaft, power transmission devices between said shaft and the gate adapted to actuate the latter to open and close the same during the final operative movements of the shaft, of a latch lever adapted to secure said gate in its open or closed positions, cable devices connecting with said lever at one end 20 25

and with a bell-crank lever at its other end, said bell-crank lever, and a cam mounted upon said shaft and adapted to engage said bell-crank to lift said latch in advance of the gate-actuating movements of said devices. 30

8. Gate actuating mechanism comprising, in combination, a support, a gate pivotally mounted to swing from said support, a shaft journaled for oscillation in said support, a weighted lever rigidly connected to said shaft, apparatus extending for a distance from said gate for raising said lever over the center of the shaft, means interposed between the pivot of said gate and said shaft to transmit motion therebetween, and devices on said shaft engageable with said means during the period wherein said weight is falling when past said center. 35 40

Signed at Irondale, Wash., this 15th day of May, 1913.

MICHAEL DIORENZO.
